Correction in Letters Patent No. 390,195.

It is hereby certified that in Letters Patent No. 390,195, granted September 25, 1888, upon the application of John T. Wilson, of Pittsburg, Pennsylvania, for an improvement in "Car-Couplings," an error appears in the printed specification requiring the following correction: In line 12, page 2, the word "number" should be stricken out and the word members inserted instead, and that the said Letters Patent should be read with this correction therein; that the same may conform to the record of the case in the Patent Office.

Signed, countersigned, and sealed this 2d day of October, A. D. 1888.

[SEAL.]

D. L. HAWKINS,
Assistant Secretary of the Interior.

Countersigned:

BENTON J. HALL,

Commissioner of Patents.
